EXOTHERMIC DEVICE

Ferdinand Racen, University City, Mo., assignor
to W. G. Shelton Company, St. Louis, Mo., a
corporation of Missouri

Application September 11, 1942, Serial No. 457,941

7 Claims. (Cl. 132—36.2)

The invention relates to exothermic pads and is particularly adapted for pads used in the waving of human hair. The invention consists more particularly in a novel container for the exothermic material.

Reference is made to the present applicant's Patent No. 2,110,677, issued March 8, 1938, disclosing an exothermic material container, one side of which consists of paper, or other material which is readily permeable by moisture, and the other side of which consists of material which is highly resistant to the passage of moisture and preferably is a metal foil which will reflect heat generated in the container.

As is well known, the present demand for most metals and metal foils for war munitions and supplies is so great that many metals are obtainable for general use. This condition restricts and eventually may prevent the manufacture, sale and use of the preferred construction of the device described in the above-mentioned patent.

The present invention has general objects similar to those of the invention described in the above-mentioned patent and has the additional object of eliminating the need of metal foil in the container without detracting from the effectiveness of the container for its intended purposes.

Another object of the invention is to decrease the expense of an exothermic pad of the class described.

These and other detailed objects of the invention are attained by the structure described below and illustrated in the accompanying drawing in which—

Figure 1 is a view of one side of a container for exothermic material, portions of one wall of the container being broken away and indicated diagrammatically to more clearly illustrate its construction.

Figure 2 is a view of the opposite side of the container.

Figure 3 is a longitudinal section taken on the line 3—3 of Figure 2, the thickness of the parts being increased in proportion to their width and length to better illustrate the construction.

The container consists primarily of an envelope 1 of paper or like material through which powdered material will not sift but through which moisture, applied to its outer face, will be readily transmitted to the interior of the envelope and to its contents. This envelope may be formed of a single sheet of material doubled on itself and provided with tabs 2, 3 and 4 to be folded over as indicated. Tabs 2 and 3 are secured to the sur-

face over which they are folded by adhesive in the initial construction of the envelope and tab 4 is left unfolded until after the exothermic material is inserted. Tab 4 is then folded over as shown in Figure 2 and secured by adhesive in the same manner as tabs 2 and 3.

Prior to filling the envelope with the exothermic substance and preferably prior to formation of the envelope, there is applied to an area of 10 the paper corresponding to one wall of the finished envelope successive imprints of ink forming a substantially solid coverage for the selected area. Preferably the first of these imprints 5 is of any ordinary printer's ink, for example as 15 may be made from a linseed oil base with additions of resin, soap, pigment and drier, as may be customary.

Over this initial imprint, which acts somewhat as a filler for the paper and a backing for other 20 imprints, there is applied one or more imprints or layers of a metallic ink such, for example, as 25 consists of a body of ordinary ink to which has been added a quantity of metallic powder. An example of such an ink would comprise fifty per cent of ordinary printer's ink and fifty per cent of ground bronze. Two such imprints or layers are indicated at 6 and 7.

After this imprinting, the envelope is completed and is filled with exothermic material 8 and flap 4 folded over and sealed as shown in 30 Figures 2 and 3. An exothermic pad so constructed may be manufactured, stored, shipped and handled freely up to and throughout its 35 application without loss of exothermic material, as characterizes the use of exothermic pads formed of meshed fabric or of paper which is to be perforated prior to its application to the hair.

When the pad is used, a strip 9 of flannel or 40 similar material may be wrapped around the wound strand of hair and the pad may be applied to the wound strand of hair with the plain paper wall next to the saturated strip 9. Spring 45 clips or other holding means are then applied over the pad to hold it in place. The moisture from the saturated strip will seep through the paper and start the exothermic reaction in the substance contained in the envelope and thereby generate the heat required for the waving operation. Instead of using a strip 9, the inner face 50 of the pad may be moistened by a brush or swab or the pad may be dipped bodily into a quantity of reaction-starting fluid.

The oil-varnish-metal components of the imprinted inks render the imprinted portion of the envelope impervious to moisture, at least to the

quantities of moisture applied to the envelope from the moisture containing strip 8 or otherwise. The same ingredients of the imprinted ink reflect the heat generated in the pad through the inner face of the container and the pad toward the strand of hair which is being waved and restrict radiation of the heat away from the hair.

The conformation and the method of forming the envelope may be varied and materials other than those mentioned, but having similar characteristics, may be substituted for the moisture-insulating and heat-reflecting imprints without departing from the spirit of the invention, and the exclusive use of such and other modifications coming within the scope of the claims is contemplated.

What is claimed is:

1. As a new article of manufacture, a container and an exothermic substance therein, said container comprising a pocket-like member formed of material which readily transmits to said substance moisture applied to the exterior surface, one wall of the container being provided with a coating of substantially moistureproof adhesive fluid.

2. A device as described in claim 1 in which the coating of the one wall of the container includes metallic ingredients for reflecting the heat generated in the device.

3. A device as described in claim 1 in which the coating of the one wall of the container com-

prises an imprint of a metallic ink substantially throughout its area.

4. A device as described in claim 1 in which the pocket-like member comprises an envelope 5 of paper and the coating consists of an imprint of a metallic ink extending substantially continuously over one side of the envelope.

5. A container for exothermic substance comprising an envelope of paper-like material which 10 is readily permeable by moisture, the envelope having one wall imprinted substantially throughout its area with a layer of metallic ink.

6. An imperforate envelope for containing exothermic material and applicable therewith as 15 an individual unit to a wound strand of hair, said envelope being made of material characterized by a high degree of capillarity and one wall of said envelope being imprinted substantially throughout its area with successive layers 20 of a metallic ink to render that wall impervious to moisture and reflectent of heat.

7. A container for exothermic substance comprising an envelope of paper-like material which is readily permeable by moisture, there being a 25 layer of ordinary printer's ink imprinted on one wall of said envelope substantially throughout its area and there being a layer of metallic ink imprinted over said first-mentioned layer substantially throughout the area of the envelope wall.
